ASH TRAY

Otto Bergman, Upper Darby, Pa., assignor of one-half to William F. Taylor, Philadelphia, Pa.

Application August 30, 1950, Serial No. 11,985

Term of patent 14 years

(Cl. D85—2)

To all whom it may concern:

Be it known that I, Otto Bergman, a citizen of the United States, residing at Upper Darby, Pennsylvania, have invented a new, original, and ornamental Design for an Ash Tray, of which the following is a specification, reference being had to the accompanying drawing, constituting a part hereof.

Fig. 1 is a perspective view of an ash tray, showing my new design;

Fig. 2 is a top plan view thereof, to a reduced scale;

Fig. 3 is a side elevational view thereof, to a reduced scale; and

Fig. 4 is an exploded perspective view thereof.

I claim:

The ornamental design for an ash tray, substantially as shown.

OTTO BERGMAN.
